UNITED STATES PATENT OFFICE.

WILLIAM GEORGE REVEL, JR., OF WASHINGTON, DISTRICT OF COLUMBIA

BOTTLE-CAP.

1,043,359.

Specification of Letters Patent. Patented Nov. 5, 1912.

Application filed April 11, 1912. Serial No. 690,018.

To all whom it may concern:

Be it known that I, WILLIAM G. REVEL, Jr., citizen of the United States, residing at Washington, District of Columbia, have invented certain new and useful Improvements in Bottle-Caps, of which the following is a specification.

This invention relates to bottle caps and has as its object to provide a cap which, while it will effectually seal the bottle to which it is applied may be readily removed without the use of an opener.

The cap embodying the present invention is of the crown type and is formed of two sections, means being provided for normally and rigidly connecting the sections and this means being adapted to be removed by hand when it is desired to remove the cap.

For a full understanding of the invention reference is to be had to the following description and accompanying drawing, in which:—

Figure 1 is a perspective view of the cap embodying the present invention, applied to a bottle. Fig. 2 is a similar view but illustrating the connecting strip for the two sections of the cap partly removed. Fig. 3 is a vertical transverse sectional view through the cap applied. Fig. 4 is a similar view through the cap taken in a plane at right angles to the plane of Fig. 3. Fig. 5 is a view partly in top plan and partly in horizontal section.

Corresponding and like parts are referred to in the following description and indicated in all the views of the accompanying drawing by the same reference characters.

The cap embodying the present invention somewhat resembles the ordinary crown cap in that it consists of a crown having a depending crimped rim and the said cap is formed in two sections each of which consists of a substantially semi-circular crown portion 1 and a substantially semi-annular depending rim 2 which is crimped as at 3 at the time of application of the cap to a bottle. The meeting edges of the crown portions 1 of the sections of the cap are indicated by the numeral 4 and when these sections are properly assembled their said edges contact as clearly shown in Fig. 4 of the drawing.

The sections of the cap are held assembled by means of a strip 5 which may be of tin or any other suitable metal, and this strip is soldered to the meeting edge portions of

the said sections. The strip 5 extends from the lower edge of the rim 2 of the cap, at one point, vertically upon the outer side of the said rim and transversely across the crown portions of the sections and downwardly upon the rim at a diametrically opposite point. This latter end of the strip extends below the lower edge of the rim as indicated at 6. The strip 5 is of course applied to the sections comprising the cap before the cap is placed in the capping machine. The portions of the strip 5 which lie against the rims 2 of the cap sections are formed with crimps 7 which engage with the crimps at the ends of the said rim portions 2, each of the said portions of the strip being preferably formed with two or more of the said crimps so that when the strip is applied to the cap the crimps 7 will overlie or engage against a corresponding number of crimps 3 at the ends of the rim portions 2.

As illustrated in Fig. 5 of the drawing, the end-edges of the rim portions 2 are preferably so located that when the sections of the cap are assembled these meeting edges are located between two of the crimps 3. As stated, each of the portions 7 of the strip 5 is formed with two or more crimps and these crimps engage over or embrace those crimps between which the meeting edges of the rim portions of the sections of the cap occur. Thus, when the cap is applied, the engagement of the crimps in the strip 5 with the crimps of the rim portions 2 will serve to hold the sections of the cap securely against separation.

It will, of course, be understood that the solder employed in securing the strip in place is the means primarily employed for uniting the sections, but that the crimps in the said strip so firmly lock the ends of the rim portions 2 together as to prevent buckling of the cap as a whole.

When it is desired to remove the cap the finger-piece 6 is grasped and the strip 5 is ripped up, as shown in Fig. 2 of the drawing, whereupon the tendency of the cap to expand will result in a separation of the meeting edges of the sections thereof, also as shown in the said figure. When the sections have been separated to about the extent shown in Fig. 2, the cap may be readily removed from the mouth of the bottle, and if the strip is entirely pulled from the sections they are separated completely, as will be understood.

Having thus described the invention what is claimed as new is:—

1. A bottle cap comprising sections each having a substantially semi-circular crown portion and depending substantially semi-annular rim portion, the said sections being disposed with the chordal edges of their crown portions and the end-edges of their rim portions abutting, and a strip secured 10 to the surface of the sections adjacent their meeting edges and extending from the edge of the rim at one point and across the crown portions and to the edge of the rim at a diametrically opposite point, the strip 15 having its last mentioned end projecting below the lower edge of the rim to form a finger-piece.

2. A bottle cap comprising sections each having a substantially semi-circular crown 20 portion and a depending substantially semi-annular rim portion, the said sections being disposed with the chordal edges of their crown portions and the end-edges of their

rim portions abutting, and a strip secured 25 to the surface of the sections adjacent their meeting edges and extending from the edge of the rim at one point across the crown portions at their line of juncture and to the edge of the rim at a diametrically opposite point, the strip having its last mentioned 30 end projecting below the lower edge of the rim of the cap whereby to form a finger-piece, the depending rim portions of the cap sections being crimped and the portions of 35 the strip which lie thereagainst being also and correspondingly crimped whereby the crimps in the strip engaging the crimps in the depending rim portions will tend to hold the sections of the cap against separation. 40

In testimony whereof I affix my signature in presence of two witnesses.

WILLIAM GEORGE REVEL, JR. [L. S.]
